UNITED STATES PATENT OFFICE.

WILLIAM JOHNSON, OF GREEN POINT, LONG ISLAND, NEW YORK.

COMBINATION SINK HANGER AND OUTLET FIXTURE.

Application filed September 7, 1922. Serial No. 586,629.

To all whom it may concern:

Be it known that I, WILLIAM JOHNSON, a citizen of the United States, residing at Green Point, Long Island, in the county of Queens and State of New York, have invented certain new and useful Improvements in a Combination Sink Hanger and Outlet Fixture, of which the following is a specification.

10 My invention relates to an improved hanger and outlet fixture for kitchen sinks, wash basins, laundry tubs and the like.

15 Porcelain kitchen sinks, for example, are preferably constructed in one piece, i. e. the sink proper and back wall are cast integral with each other, and the upper edge of the back section is provided with depending lugs which engage suitable recesses in a separate hanger or bracket to support the entire sink in position against a room wall.

20 The back wall of the sink is further provided with two openings through which the outlet taps project from the hot and cold water supply pipes. As a general rule, in

25 the course of building construction the piping is completed before the floors and walls are finished, and this makes it necessary to connect the upstanding water supply pipes during this early stage in the construction

30 of the building. When the building has reached the point where the sinks are to be installed the plumber is obliged to fit the entire work to the two upstanding pipes, an operation which involves considerable difficulty and requires a great amount of time.

35 This operation consists in first locating the correct position of the sink as to its height and then with respect to the supply pipes, so as to bring the opening in the back wall of

40 the sink into register with the pipes. The position of the hanger or bracket is then indicated on the room wall and after removing the sink the hanger is permanently secured against the room wall. It has been

45 found that during this operation it is practically impossible to prevent a slight variation in the position of the hanger and when the taps are to be attached through the openings and into the ends of the upstanding

50 supply pipes the openings themselves will not be in a correct position. While these discrepancies in most cases, are only slight, it requires considerable time for the plumber to make the necessary adjustments to align

55 the openings with the ends of the pipes, and the time consumed in making these adjust-

ments is practically wasted. It is the principal object of the present invention to provide a hanger of the character hereinafter described, on which a sink is supported in the usual manner from its back wall and which is further provided with integral pipe connections, the outlet openings thereof being adapted to coincide with the openings in the wall of the sink, whereby the necessity of aligning the openings with the pipes is avoided.

A further object of the invention is to afford facilities within the hanger for adjustment thereof, whereby various sizes of sinks may be accommodated, and pipe connections requiring unusual distances between centers may be brought into alignment with the openings in the back wall of the sink.

The invention is described in the following specification, set forth in the appended claims and illustratively exemplified in the accompanying drawings, in which,

Figure 1 is a perspective view of my improved hanger; Figure 2 is a substantially vertical section of the hanger taken through a pipe connection and showing the outline of a sink in dotted lines.

Referring to the drawings, 10 denotes the usual porcelain kitchen sink having an integral back section 11 provided with depending lugs 12 and outlet openings 13. The outlet openings 13 are spaced a standard distance apart and are adapted to be aligned with the upstanding hot and cold water supply pipes 14, as shown in Figure 1.

The sink is supported on a bracket or hanger designated 15 which consists of an integral casting having a flat narrow wall plate 16 and downwardly projecting pipe connections 17. The wall plate 16 divided into two sections, each thereof being provided with a plurality of longitudinal slots 18 disposed midway of its width and adapted to receive screws 19 which attach the plate to the room wall 20. At the outer ends of the plate 16 and disposed along the upper edge thereof are offset sections in the body of the plate which form channels or grooves 21 to receive the depending lugs 12 in the back wall of the sink.

The pipe connections 17 are cast integral with the wall plate 16 and comprise tubular members closed at their upper ends and projecting downwardly over the face of the plate. At a suitable distance from the plate and disposed in the front wall of both mem-

bers are outlet openings 22 which are axially aligned with the openings 13 in the wall of the sink 10 when the latter is in position, as clearly illustrated in Figure 2. The outlet openings 22 are interiorly threaded to receive the nipples 22^a of taps 23 projecting through the openings 13. The vertical portions of the connections 17 which project below the outlet openings 22 are threaded 10 to receive the ends of the upright water supply pipes 14. In order to suitably strengthen the lower portion of the pipe connections below the wall plate 16 the former are provided with bridge pieces 24 15 extending therebetween and cast integral therewith.

The construction of the pipe connections 17 provide air chambers 25 above the outlet openings 22 so as to afford a cushion of air 20 against which the pressure of water will be exerted when the taps are suddenly closed.

The operation of installing a sink by means of the present hanger is substantially as follows: Assuming that the sink is to be placed a certain distance above the floor, this distance is marked off with the added height of the back wall 11. This mark will give the proper height at which the hanger 15 is to be secured. The lateral position of the hanger is then finally determined by the upright pipes 14 which, as previously described, are in position before the installation of the sink takes place. Having aligned the intake openings in the connections 17 35 with the centers of the pipes 14 the wall plate is screwed to the room wall. The number of slots 18 in the wall plate 16 gives a wide latitude within which the plumber may work so as to be able to strike a beam with the screws 19. It has also been found at 40 times that lateral adjustment of the hanger 15 becomes necessary, such an adjustment with the present construction merely requiring the screws to be loosened and the hanger 45 to be moved along the slots 18 to proper position. The supply pipes 14 are then connected to the inlet ends of the pipe connections 17 and the hanger 15 is ready to receive the sink 10. The lugs 12 in the back 50 wall of the sink are introduced into the grooves 21 and the whole fixture dropped in position. The important feature of this

construction resides in the fixed relation of the grooves 21 and the outlet centers of the connections 17, so as to always bring the 55 openings 13 in the back wall of the sink into alignment with the outlet openings 22. The operation is completed by introducing the threaded ends 22^a of the taps 23 into the 60 openings 13 and outlet openings 22. 60

The above installation is effective only when it is not found necessary to vary the distance between the pipe connections. Due to the body of the wall plate 16 being made in two pieces A and B, further adjustment 65 may be had by changing the relative position of the two parts with respect to each other. The member A is provided with offset end portions 26 in the wall plate 16 and bridge 70 24, the portions being provided with longitudinal slots 27 adapted to register with slots 28 in the end of the other member B. By adjustment of the member A relatively to member B the centers of the pipe connections 17 and grooves 21 may be changed to 75 accommodate various positions of the supply pipes, and types of sinks.

Having described my invention what I claim and desire to secure by Letters Patent is:

1. Means for supporting sinks, comprising a divided straight wall bracket provided with offset pockets to receive the projections of a sink member, said bracket being further provided with longitudinally disposed openings to receive fastening means adapted to attach the bracket to a vertical surface, pipe connections integral with said bracket and comprising outwardly and downwardly projecting hollow members 90 provided with transverse outlet openings to receive taps and inlet openings at the free ends to receive stand pipe connections, and a divided bridge piece integral at opposite ends with the said hollow members. 95

2. Means for supporting sinks, as claimed in claim 1, in which the said bracket and bridge pieces are provided with portions which overlap and capable of adjustment with respect to each other to change the distance between the axes of the said hollow members, substantially as described. 100

In testimony whereof I affix my signature.
WILLIAM JOHNSON.
